GUARD FOR SLEDS

Olmer Olson, Froid, Mont.

Application April 30, 1936, Serial No. 77,269

4 Claims. (Cl. 280—1)

My invention relates to improvements in guards for use on a sled to confine a rider, particularly a child, on the sled.

The primary object of my invention is to provide a device of this character which may be readily and securely attached to a sled of the usual construction, or detached therefrom, by a small child and which is extensible for attachment to sleds of different lengths.

10 Another object is to provide a guard of the character and for the purposes set forth embodying handle bars for use in propelling the sled and functioning as a brace between the sled and the guard proper.

15 Another object is to provide a guard for the purposes set forth which is light in weight, strong and durable, and inexpensive to manufacture.

20 Other objects together with the exact nature of my improvements will become apparent when the following description and claims are read with reference to the accompanying drawings.

In said drawings:

Figure 1 is a view in side elevation of a sled having my improved guard attached thereto.

Figure 2 is a view in top plan.

Figure 3 is a view in rear elevation.

Figure 4 is a view in longitudinal section taken on the line 4—4 of Figure 1.

Figure 5 is a view in transverse section taken on the line 5—5 of Figure 1 looking rearwardly of the sled.

Figure 6 is a view in transverse section of a modification of the invention.

Figure 7 is a fragmentary view in side elevation of the modification shown in Figure 6.

Figure 8 is a view in transverse section of a further modification of my invention, and

Figure 9 is a detail view of still another modification of my invention.

40 Referring to the drawings, the sled to which my guard is attached is of the usual type embodying runners 1 front and rear pairs of upright struts 2 supporting front and rear cross bars 3 and 4, respectively, which in turn support the usual side bars 5 and top boards 6 the outer ones of which are spaced from the side bars 5.

The guard of my invention, in its preferred embodiment, comprises a single piece back section 7 which includes a pair of opposed uprights 8 having looped lower ends 9, a pair of opposed horizontally disposed side arms 10 extending forwardly of the upper ends of the uprights 8, respectively, to provide arm rests, and a back supporting panel 11 extending between the rear edges of the uprights 8 preferably from end to

end thereof. The described back section 7 is formed preferably of a single piece of thin gauge metal of the requisite rigidity. The panel 11 is transversely curved outwardly and inclined upwardly and rearwardly to contribute to the comfort of the rider.

The back section 7 is adapted to be attached to the sled by means of the looped ends 9 which are positioned over the rear ends of the side bars of the sled 5 against the rear cross bar 4. The side arms 10 of the section 7 are provided with forwardly and downwardly curved extensions 12, preferably also of thin gauge metal, telescoping over the arms 10 and provided at their forward ends with means for securing the guard to the side bars 5. The securing means preferably takes the form of a pair of spaced apart lugs 13 on each extension 12 projecting from the outer faces of the extensions at right angles thereto to straddle the side bars 5. In securing the extensions 12 to the side bars 5 said extensions are flexed inwardly and interposed between adjacent edges of the top boards 6 and side bars 5 and are then flexed outwardly to straddle said side bars 5 and pushed rearwardly of the side arms 10 to locate their front ends against the front cross bar 3 of the sled. In this connection it may be stated that the metal of which the side arms 10 and extensions 12 are formed is to be sufficiently resilient to permit the flexing action described. In sleds as commonly constructed the space between the outside top boards 6 and the side bars 5 of the sled is usually sufficient to permit the extensions 12 to be secured to the side bars 5 in the manner described. However, in the event that it is desired to attach the guard to a sled which is deficient in this respect the side edges of the outer top boards 6 may be notched, as shown at 14, to provide the required space.

The side arms 10 and extensions 12 are yieldingly connected together at their juncture so that the guard may be extended or contracted to fit against cross bars of sleds of various lengths. The yielding connection preferably comprises semi-circular sockets 15 spaced along the front ends of the side arms 10 and a rounded stud 16 mounted in each extension to seat in said sockets and urged by a spring 17 to seat therein.

The handle bars comprise a substantially U-shaped frame of metal including a pair of opposed pusher arms 18 connected at one end by a transverse bar 19 and a wooden hand grip bar 20 suitably secured to the transverse bar 19. The pusher bars 18 are secured to the side bars 5 of the sled and to the side arms 10 of the section 7.

to incline upwardly and rearwardly and by means of the following.

- The free ends of said bars 18 are bifurcated, as indicated at 21 to straddle the side bars 5 and extend below the same. Bolts 22 passing through the extending portions of the bifurcations 21 and having wing nuts 23 threaded thereon detachably secure the bifurcated ends of the pusher bars 18 to the side bars 5. Intermediate their ends the pusher bars 18 are detachably secured to the inner faces of the side arms 10 by plates 24 clamped against the outer sides of the bars 10 by bolts 25 passing through said bars and plates and wing nuts 26 on said bolts.
- In Figure 6 the extensions 27 have been shown as provided with additional means for securing them to the side bars 28 of the sled and having the form of latches 29 pivotally mounted as at 30 to swing over the outside edges of the side bars 28. The latches 29 are each provided with a resilient manipulating arm 31 having a tooth 32 thereon adapted to seat in a notch 33 in the related extension 27 with a snap action to hold the latch in effective position.
- In Figure 8 the ends of the extensions 34 have been shown as connected together by a toggle lock comprising a pair of toggle links 35 pivoted to said extensions as at 36 and to each other as at 37 and operative toward the floor boards 38 of the sled into a dead center position to spread the extensions 34 against the side bars 36 of the sled. The toggle links may be disposed to operate parallel with the floor boards either forwardly or rearwardly if desired.
- As shown in Figure 9 the side arms designated 39 and 40, in this instance, may be provided with bolt holes 41, respectively, for securing the same together by bolts not shown.
- The modifications disclosed relate to the means for securing the extension arms of the guard to the side bars of the sled only, but it is to be understood that right is herein reserved to modifications of the invention in other respects falling within the scope of the claims appended hereto.
- What I claim is:
1. A guard for attachment to a sled having front and rear cross bars and side bars extending beyond said cross bars said guard comprising, an upright back rest and a pair of arm rests 50 extending forwardly from said back rest upon opposite sides of said sled, the back rest being provided at its lower edge with attaching means telescoping over the rear ends of said side bars and slidably thereon, the arm rests being resilient for flexing inwardly and reaction outwardly and having attaching means at their front ends adapted to be interlocked with said side bars by such reaction of said arms, said arm rests comprising telescopic interlocking sections manipulative to lengthen and shorten the arm rests whereby said back rest attaching means and said arm attaching means may be located against opposite edges of the rear and front cross bars,

respectively, to obviate endwise slipping of said guard on said sled.

2. A guard for attachment to a sled having front and rear cross bars and side bars extending beyond said cross bars said guard comprising, an upright back rest and a pair of arm rests extending forwardly from said back rest upon opposite sides of said sled, the back rest being provided at its lower edge with attaching means telescoping over the rear ends of said side bars and slidably thereon, the arm rests being resilient for flexing inwardly and reaction outwardly and having attaching means at their front ends adapted to be interlocked with said side bars by such reaction of said arms, said arm rests comprising telescopic interlocking sections manipulative to lengthen and shorten the arm rests whereby said back rest attaching means and said arm attaching means may be located against opposite edges of the rear and front cross bars, respectively, to obviate endwise slipping of said guard on said sled, and a pair of push rods upon opposite sides of the guard, respectively, removably connected to said guard and comprising means for connecting said rods to said side bars.

3. In a guard for attachment to a sled having front and rear cross bars and side bars extending beyond said cross bars said guard comprising, a back rest provided at its lower edge with looped extensions adapted to slide over the rear ends of said side bars, and a pair of arm rests extending forwardly from said back rest upon opposite sides of the sled, respectively, said arm rests having bifurcated front ends extending laterally and outwardly from said ends for positioning sidewise over said side bars, said arms being resilient for flexing inwardly to facilitate positioning of said bifurcated ends relative to said side bars and reactive outwardly to clamp said bifurcated ends against said bar, and said arms comprising telescopic sections manipulative to vary the distance between said looped extensions and said bifurcated ends whereby said extensions and ends may be located against the rear and front cross bars, respectively, and latching devices for holding said telescopic sections against relative movement.

4. A guard for attachment to a sled comprising, a back rest having a pair of looped extensions at its lower edge upon opposite sides of said rest, respectively, and a pair of arm rests extending from opposite side edges thereof at an angle thereto and integral with said back rest, a pair of extensions telescopically mounted on the free ends of said arm rests, respectively, and having right angled bifurcated front ends extending inwardly of said guard, and a pair of push rods removably secured intermediate their ends to said arm rests at the juncture of the latter with said back rest, said push rods having front bifurcated ends disposed intermediate the back rest and the extensions.

OLMER OLSON.
